UNITED STATES PATENT OFFICE.

WILLIAM F. LAUTENSCHLAGER, OF CINCINNATI, OHIO.

FOLDING-MACHINE.

1,121,852.

Specification of Letters Patent. Patented Dec. 22, 1914.

Application filed October 28, 1914. Serial No. 868,855.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Folding-Machines, of which the following is a specification.

My invention relates to folding machines adapted for progressively folding the margins of flexible material, such as leather, cloth and the like, and is adapted for folding the margins of uppers of boots and shoes and parts thereof, such as vamps, quarters, foxings, button-flies and the like, and for other purposes.

It is the object of my invention to provide novel means in a machine of the character mentioned whereby to control the folding of the margin; further to provide a novel fold-laying instrumentality arranged to be adjusted into various positions crosswise of the margin being folded and acting thereon in novel manner; further to provide such fold-laying instrumentality having a narrow pressing edge at both sides of which the fold of the margin being folded has relief from pressure, said fold-laying edge extending crosswise of the margin being folded; further to provide a fold-laying edge extending in a direction toward the center upon which the portion of the material having a convex margin is turned during the folding operation; further to provide means to change the direction in which said fold-laying edge extends crosswise of the margin being folded; and, further to so arrange said last-named means as to be under the control of the operator during the operation of the machine.

It is the object of my invention, further, to provide means whereby to impart a buckling to the base of the fold of the margin being folded for presenting said fold in opposition to a pressing fold-layer; further to provide means for imparting a transverse buckle to the body of the margin being folded adjacent to the folder, fold-layer and presser-foot for aiding in determining the line of the fold; further to provide novel means whereby to lay a convex margin being folded in puckers, so that each pucker is

formed by a plurality of impressions of the pressing fold-layer; further to provide means whereby the puckering of the material is preceded by a reverse buckling of the fold of the margin being laid, the buckled portion being subsequently acted on by the fold-layer; and, further to provide novel arrangement of mechanism whereby the margin being folded is acted on in step-by-step relation by a folder, a buckling device, and a fold-layer, and selectively by a fold-presser, in the order named.

It is the object of my invention, further, to provide a fold-layer adjustable toward and from a fold-buckling device acting on the margin in advance of said fold-layer; further to provide a fold-buckling device and a fold-presser, and fold-layer adjustable between said fold-buckling device and fold-presser; further to provide means whereby said adjustments are controlled by the operator while the material is being folded; and, further to provide novel means whereby said control is effected.

The invention will be further readily understood from the following description and claims, and from the accompanying drawings.

I have exemplified my invention as embodied in a machine having operating devices, such as those shown and described in my application for Letters Patent of the United States, filed February 12, 1914, Serial No. 818,250, and my present invention is an elaboration of the invention shown, described and broadly claimed in my aforesaid application, to which reference is made for greater particularity.

In the drawings; Figure 1 represents a side elevation of the head end of a folding machine embodying my invention. Fig. 2 is a front end elevation of my improved device. Fig. 3 is a horizontal plan section of the same, partly broken away, on a line corresponding to the irregular line 3-3 of Fig. 1. Fig. 4 is a vertical cross-section, partly broken away, taken on the line 4-4 of Fig. 1, illustrating the manual control for the fold-layer. Fig. 5 is a detail in section on the line 5-5 of Fig. 4. Fig. 6 is a plan view of the parts acting on the margin being folded for folding the same,

showing the fold-layer in rearward position, and indicating the action of the parts on a straight margin being folded. Fig. 7 is a similar view showing said parts with the 5 fold-layer adjusted into forward position for acting on the convex margin of flexible material. Fig. 8 is a detail of the same in vertical section on the line 8—8 of Fig. 7, showing the action of the fold buckling device. Fig. 9 is a similar view of the parts with the fold-layer adjusted into rearward position and acting on a concavely curved margin, the snipping mechanism being operative for snipping the margin. Fig. 10 is a vertical section taken on the line 10—10 of Fig. 1, showing a straight margin being folded, the feeding-foot being at its rear limit of movement just prior to raising, and the hammer in descending relation. 15 Fig. 11 is a vertical cross-section of the same taken on the line 11—11 of Fig. 10. Fig. 12 is a perspective view of the parts concerned in the feeding, buckling, fold-laying and fold-pressing movements, a convex margin 25 being folded; and, Fig. 13 is a perspective view of the fold-buckling, laying and pressing parts in separated relation.

For elucidation it may be here stated, that in machines of the character mentioned, the 30 operator's position is in front of that portion of the machine shown in Fig. 1, and to the right of the machine as shown in Fig. 2; and that in the present description, the terms "front", or "advanced", in describing a part or relation of parts, means that portion or position toward or near the operator, and the terms "rear" or "retracted" mean that portion or relation distanced from or away from the operator.

40 The embodiment of my invention herein shown and described is merely an exemplification, my invention being sufficiently broad to cover any other embodiment within the scope of the appended claims.

45 In machines of this character, the flexible material exemplified at 11, 12, and 13, is arranged to be fed with a step-by-step movement, instanced in the present exemplification as accomplished by means of an oscillating feeding-foot 14. The feeding-foot is 50 arranged to move downwardly and away from the operator for the feeding movement and upwardly and toward the operator for the returning movement, for intermittently feeding the material.

The feeding-foot is on a stem 15 which reciprocates up and down in bearings 16 in the slide-frame 17. The stem has a guide 18 adjustably clamped at suitable positions 60 lengthwise thereof by means of a clamp-bearing 19. This guide has a guideway 20 in which a pin 21 on a rocker-arm 22 is received, the rocker-arm being fast on a rock-shaft 23, and acts to raise and lower the 65 feeding-foot.

The back and forth movements of the feeding-foot are accomplished in the present exemplification by providing the slide-frame 17 with bearings 25, which slide lengthwise on guide-rods 26 in the head 27 of the upper bracket 28 of the main frame 29. The slide-frame is provided with a rack 30 fast thereon, with which a segment-gear 31 fast on a rock-shaft 32 meshes.

70 Suitable means are provided, such for instance, as shown and described in my aforesaid application, for rocking the rock-shafts 23 and 32 for accomplishing the movements of the feeding-foot above mentioned.

75 In the present exemplification a feed-bar 36 acts in opposition to the feeding-foot, this feed-bar moving back and forth in a guideway 37 in the lower arm 38 of the main frame, this guideway having an extension 39 in the table 40 of the machine. The bracket 28 and arm 38 may extend laterally from a suitable main frame or column as shown in my aforesaid application. The feed-bar is mounted on anti-friction rollers 41 journaled on studs 42 at the respective ends of the path of movement of the feeding-foot. The feed-bar is normally resiliently held toward the in-feeding end of its path by means of a spring 43 located 80 in the recess 44 of the feed-bar between a shoulder 45 on the feed-bar and a shoulder 46 in the table. The ends of the feed-bar are provided with depending lugs 47 whose inner faces are exemplified as described on 85 arcs 48 coinciding with the circles of the peripheries of the anti-friction rollers, acting as stops for the feed-bar against said rollers. The table is provided with a depression 49, the bottom of which is formed 90 by the feed-bar. The feed-bar is moved in the feeding movement by contact of the material therewith, which contact is relieved upon raising of the feeding-foot for permitting return of the feed-bar by means of 95 the spring.

100 The edge of the material is arranged to be guided against a side-guide 51 arranged to be adjustably clamped to the table by means of a clamp-screw 52 threaded into 105 the table through a slot 53 in the guide.

110 The margin of the material is arranged to be fed past a folder 55, shown as a folding-block provided with a folding throat 56, and secured to the table by means of a 115 screw 57.

120 Snipping means, exemplified as an upper knife 61 coacting with a lower cutter-block 62, arranged to cut or snip the margin of the material when desired, for instance in 125 folding concave curves, as indicated in Fig. 9. The cutter-block is arranged to be moved into and out of cutting relation with the upper knife, shown by being mounted on a T-slide 63, slidable in a guideway 64, 130

and held in said guideway by a plate 65. The cutter-block is adjustably clamped to the slide by means of a screw 66 received through a slot 67 in the cutter-block and threaded into the slide.

The plate is provided with lugs 68, 69, between which a crank-pin 70 is received, the crank-pin being mounted on a rocker-part 71 journaled on a stud 72 in a lug 73 of the lower arm of the frame.

An arm 75 is rigid on the rock-shaft, and has a link 76 articulated therewith. A spring 77 is received about the link between a bearing 78 through which the link passes and a collar 79 on said link. A suitable connection, as a rod 80, connects the link with a suitable treadle 74 for shifting the cutter-block manually into inoperative relation during the feeding of the material through the machine. The plate 65 is arranged to contact a set-screw 81 adjustably positioned in a lug 82 of the lower arm of the frame and held in adjusted position by a clamp-nut 83 for defining the cutting relation of the cutter-block with the upper knife.

The retraction of the cutter-block, shown retracted in Figs. 6, 7 and 12, permits the ready flexing of the edge of the material below the horizontal plane of the cutting edge of the cutter-block for insuring that the cutter-blade may continue its oscillations thereabove without cutting or snipping actions thereof on the material.

A presser-foot 86 is adapted to hold the material in place between feeding movements. It is exemplified as mounted on a forwardly extending arm 87 rigidly secured to a reciprocating post 88 reciprocating in bearings 89, 90, in the head 27. The post is held against rotation by means of a positioning screw 91 threaded into the bearing 90, the inner end of the screw being received in a slot 92 extending lengthwise of the post. A spring 93 received about the post between the bearing 89 and a collar 94 secured to the post causes yielding pressure of the presser-foot toward the material. The rock-shaft 23 is provided with a tap-pet-arm 95 fast thereon arranged to engage a collar 96 on the post 88, adjustably clamped on the post for intermittently raising the presser-foot during the operation of the machine, as more fully shown and described in my aforesaid application.

For manually raising the presser-foot, a lever 97 is provided, pivoted to the bearing 90 on a screw 98 and having a knob 99 thereon received between lugs 100 on the presser-foot arm 87, a spring 101 preventing jarring of the lever 97.

The upper cutter 61 is shown as a cutter-blade adjustably secured to a lever 103 by means of a clamp-screw 104 received through a slot 105 in the cutter-blade and threaded

into the lever. The lever comprises a hub 106 formed by a bearing about a cross-shaft 107, located in bearings 108 in the frame, an arm 110 to which the cutter-blade is secured, and an arm 111 with which driving connection is had for operating the lever.

The drive-shaft 112 of the machine is provided with an eccentric 113, about which an eccentric strap 114 is received. A link 115 extends from the strap and has a ball and socket connection 116 with the knife-lever. The drive-shaft is driven by suitable means, for instance by a suitable pulley or other power driving means, as more fully shown and described in my aforesaid application.

A hold-down finger 123 is arranged to project over the margin of the material to be folded, preferably in front of the feeding-foot and into adjacency with the side-guide 51. This finger is shown secured to the presser-foot by means of a clamp-screw 124 threaded into the presser-foot and received through a slot 125 in the finger.

I have provided novel means acting on the margin being folded for laying the fold and pressing the same. These instrumentalities preferably comprise a fold-buckling device, a fold-layer and a fold-presser. These parts may be mounted and operated independently, but I prefer to mount them for combined reciprocating movement, designating the parts generally as a fold-hammer 131, mounted on a lever 132 comprising a hub 133, an arm 134, and an arm 135. The hub is in the form of a bearing about a cross-shaft 136 received in bearings 137 in the frame.

Drive connection is formed with the arm 135 for operating the lever, exemplified as an eccentric 141 on the drive-shaft 112, about which a bearing 142 is received. A slide-frame 143 is received about the bearing and has slide-connection therewith. A link 144 extends from the slide-frame and has a ball and strap connection 145 with the lever, forming a ball and socket joint. This link is shown in the form of an adjusting screw threaded into a threaded socket 146 in the slide-frame and held in adjusted position by means of a lock-nut 147.

The pressing force of the eccentric 141 upon the hammer is imparted through the medium of a spring 148, between the bearing 142 and the end wall 149 of the slide frame, so that the pressure exerted by the hammer upon the margin being folded is a yielding pressure, for permitting the hammer to yield to inequalities of the material and to exert a yielding pressure upon the folded margin for pressing the same. This drive connection is more particularly shown and described in my aforesaid application.

150 is a fold-layer, exemplified as on a lever 151 pivoted on a shoulder-screw 152 received through a bearing-hole 153 in the 130

lever and threaded into the hammer. It has a narrow fold-laying and pressing edge 154 arranged to extend crosswise of the margin being folded. I prefer to provide means whereby the fold-layer is shifted so as to present its fold-laying edge in different directions in the plane of the margin being folded, when in fold-pressing relation, depending on whether a straight or concave 10 curved margin, or a convexly curved margin, is being folded. The position of the fold-layer with relation to the margin being folded is preferably under the control of the operator during the operation of the machine, so that when a convex curve is reached, the fold-layer may, in the present exemplification, be moved forwardly without interruption of the folding operation. For accomplishing this I provide the fold-layer lever with a pin 156. A lever 157 is pivoted by a bearing 158 about the rock-shaft 32 and has an arm 159 to which a laterally extending arm 160 is secured. This laterally extending arm is provided 20 with a fork 161, between the tines of which the pin 156 is received so as to swing the fold-layer when the lever 157 is operated. The fork 161 is arranged upon an arc described from the pivot of the hammer-lever 25 as a center, so that the operative relation between the pin and fork may be maintained irrespective of the position of the hammer or of the position of the pin. The lever 157 is provided with an arm 162 having a finger-part 163 thereon for manually operating the lever.

A helical spring 164 is received about the shaft 32, one end thereof being connected with the lever 157, as shown at 165, 40 the other end thereof being connected with a collar 166, as shown at 167, the collar being secured to the rock-shaft by a set-screw 168.

The fold-layer is arranged to be in forward position when laying the fold of the margin along convex curves and in rearward position when laying the folds of straight margins or margins having concave curves.

50 Means are provided for positioning the fold-layer in intermediate positions, which is desirable when laying the folds of margins which have only short straight portions or concave portions, as well as convex portions described on curves having comparatively long radii, in which case manual manipulation of the fold-layer during operation of the machine is in practice not necessary if such adjustment of the fold-layer 55 is made. For so positioning the fold-layer, I provide its operating lever 157 with a cam 171, pivoted to the operating lever on a shoulder-screw, 172, the cam being resiliently held in adjusted position by a cup-washer 173 between the head of said

shoulder-screw and the cam. The cam is arranged to strike a suitable stationary part, for instance, the bottom of the bracket 28, for locating the fold-layer in its adjusted position. The cam is provided with an arm 70 174 arranged for manually positioning the cam with relation to the operating lever 157.

176 is a fold-presser, which is shown rigid with the haminer, and is arranged to press the laid fold. Novel means are further 75 provided for determining the line of the fold and for presenting the fold of the margin in proper relation to the fold-layer for being readily laid, especially when folding along convex curves of short radii. I accomplish this by means of a fold-buckling device 178, which is shown integral with the hammer as an indenting point arranged to act on the base of the margin being folded. It is positioned, in the present exemplification, immediately in rear of the folding-block and in substantial cross line with the rear edge 179 of the presser-foot.

In operation, the feeding-foot acts to feed the material past the stationary folding-block which imparts an initial curl to the margin. The presser-foot descends at the end of the feeding movement of the feeding-foot for holding the material in fed relation, whereby the rear edge 179 of the 90 presser-foot presses upon the body of the flexible material in a position in substantial cross line with the rear edge of the folding-block. The margin being folded is usually skived, as shown at 180, and provided with a 100 band of cement, as shown at 181. The fold of the margin which has received its preparatory curl by the folding-block, is more readily flexed than the body of the margin. When, therefore, the fold-buckling device 105 makes contact with the margin, it presses the body of the margin into a straight line between the rear edge 179 of the presser-foot and the rear edge of the folding block, for defining the bend 182 of the fold in the 110 angle between the material-supporting face of the table and the left-hand edge of the rear of the folding-block, thus defining the line of the fold, and further causes a buckling of the fold of the margin, as indicated 115 at 183 for causing the outer end of said fold to stand more nearly upright with relation to the body of the margin, as indicated in Fig. 8. The cement upon the inner face of the margin aids in maintaining the 120 bend 182. This action upon the margin is especially desirable when folding margins having convex edges, in folding which the fold-layer is in forward position for laying the convex fold into cross puckers, as indicated in Figs. 7, 8 and 12.

When operating on margins having convex curves, especially such curves described on short radii, the fold-layer is preferably positioned for extending forwardly slant- 130

ingly across the margin being folded, and desirably across the left end of the buckling device. In feeding such margins the material is swung about a center having the center of the curvature of the margin substantially as its center of swing, and for properly laying the puckers I prefer to position the fold-laying edge of the fold-layer in a direction projecting toward said center.

10 The fold of the margin being folded, having received its buckle previous to the action thereon by the fold-layer, presents the buckled upstanding fold of the margin more nearly at right angles to the direction 15 in which the fold-layer extends and creates a tendency for laying the puckers in layers which extend rearwardly, as indicated in Figs. 7 and 12. The fold-layer presses upon the edge of the pucker thus formed, thus 20 pressing the inner cemented face opposite the pressing face of the fold-layer, upon the body of the margin, for definitely maintaining the cross lines of the pucker, as the pressure exerted in my improved device in hammering the margin upon the body of the material by means of the fold-laying portion of the hammer causes a definite laying of the pucker and attachment of the cross edge thereof to the body, this hammering being 25 sufficient to locate and maintain the puckers without subsequent pressure upon the puckers in the machine if desired.

For aiding in causing stiffness of the body of the margin in a cross line during the action of the hammer upon the margin, for determining the line of fold, and also for aiding in feeding the material, I prefer to provide the table with the depression 49, into which the feeding-foot causes depression of 30 the body of the material during the feeding movement, as indicated at 184, whereby a cross-buckle, indicated at 185, is imparted to the body of the margin adjacent to the point of operation on the fold of the margin by 35 the hammer, for stiffening the body in the line between the rear edge of the presser-foot and the stationary folding-block, for insuring that the bend 182 of the margin will be pushed into the angle between the 40 material-supporting surface of the table and the outer edge of the folding-block during the crease-determining action. Tension upon the outer edge of the fold of the margin is also relieved by causing the body of 45 the margin to be depressed in the depression in advance of the fold-laying instrumentality and at the side of the folding-block.

176 is a fold-presser which is arranged to act on the margin, for pressing the fold subsequent to the action thereon by the fold-layer. This fold-presser is preferably rigid with the hammer.

The feeding, folding and fold-hammering means are so correlated as to lay a fold in 50 manner to minimize tension upon the ex-

treme edge of the margin being folded. When a straight margin is being folded the margin is permitted to assume a comparatively long curl, as indicated in Fig. 6, and when folding convexly curved margins, the 70 fold-layer is presented in such manner as to lay cross-puckers in adjacency to each other and to insure pressure at the front and rear cross edges of said puckers for locating the same.

75 Each of the puckers is formed by a plurality of operations of the fold-layer, the first of which determines the rear cross line of the pucker and secures the pucker at its rear edge to the body of the margin by pressure of the fold-layer upon this laid-over rear cross-line of the pucker and the cement thereunder, and the second of which lays the pucker in its fold, as indicated at 187, and determines the forward cross edge of the 80 pucker by contact with and pressure upon the buckled fold of the margin, pressing said forward edge upon the cement and body of the margin for fixing said forward edge of the pucker. The laying of the fold of the 85 convex margin in regular puckers is thus assured. The pressing edge of the fold-layer is sufficiently wide to insure lasting adhesion of the pressed edges of the puckers of the fold to the body of the margin.

90 The fold-presser is arranged to be adjusted to positions between the forward margin-buckling device and the rearward fold-pressing device by means of the cam 171, for defining one limit of its path of 100 movement during manual manipulation.

Having thus fully described my invention, what I claim as new and desire to secure by Letters Patent, is:

1. In a folding machine for folding the 105 margin of flexible material, the combination of step-by-step feeding means, a folder acting to partially fold the margin, and a fold-layer having a narrow pressing face extending crosswise of the fold of the margin being laid and having relief from pressing action on said fold in rear of said narrow pressing face for the formation of a pucker and arranged to press the fold upon the body of the margin successively at the rear 110 edge and at the front edge of said pucker in a line transverse to said fold, and means for shifting said fold-layer for presenting said narrow pressing face in different directions crosswise of said fold in a plane parallel to said pressed margin when in fold-pressing relation.

115 2. In a folding machine for folding the margin of flexible material, the combination of step-by-step feeding means, a folder acting to partially fold the margin, a fold-buckling device acting upon the base of the partially folded margin to buckle the fold for presenting the outer edge of its buckled portion in upward direction, and a fold- 120 130

- layer extending crosswise of the buckled portion of the fold of the margin being laid arranged to press the fold upon the body of the margin in a line transverse to said fold.
- 5 3. In a folding machine for folding the margin of flexible material, the combination of a material-support, step-by-step feeding means, a folder arranged to partially bend the fold of the margin, a presser-foot acting 70
10 at the side of said folder and having a pressing part substantially in cross-line with the rear edge of the folding face of said folder, and a buckling device acting on the base of said fold of said margin arranged for pressing 75
15 the bend between the body and the fold of the margin into the angle between the supporting face of said material-support and said rear edge of said folding face for defining the line of the fold and buckling 80
20 said partially bent fold, and a fold-layer having a fold-pressing face extending crosswise of said fold of said margin for pressing said fold upon said body of said margin.
4. In a folding machine for folding the 90
25 margin of flexible material, the combination of step-by-step feeding means comprising an upper feeding part, a material supporting table, a folder for partially folding said margin, a presser-foot having a presser portion in substantial cross-line with the rear 95
30 edge of the folding face of said folder, and a hammer, the material supporting surface of said table having a depression therein whose rear wall is adjacent to said cross-line, and said upper feeding part arranged to press the material into said depression for forming a buckle in the body of the margin between said folder and said presser portion adjacent to said hammer.
- 35 5. In a folding machine for folding the margin of flexible material, the combination of step-by-step feeding means comprising an upper feeding part, a material supporting table, a folder for partially folding said 100
40 margin, a presser-foot having a presser-part in substantial cross-line with the rear edge of the folding face of said folder, and a hammer, the material supporting surface of said table having a depression therein at 105
45 the side of said folder whose rear wall is adjacent to said cross-line, said upper feeding part arranged to press the material into said depression for forming a buckle in the body of the margin between said folder and said presser part adjacent to said hammer for relieving the outer edge of said fold 110
50 from tension.
- 55 6. In a folding machine for folding the margin of flexible material, the combination of step-by-step feeding means, a folder, for 115
60 partially forming the fold of the margin, a fold-layer, and a fold-buckling device of the character described acting on said fold of the margin between said folder and said fold-layer.
7. In a folding machine for folding the margin of flexible material, the combination of step-by-step feeding means, a folder for partially forming the fold of the margin, a fold-layer, a fold-buckling device of the character described acting on said fold of the margin between said folder and said fold-layer, and a fold-pressing device in rear of said fold-layer. 70

8. In a folding machine for folding the margin of flexible material, the combination of step-by-step feeding means, a folder for partially forming the fold of the margin, a presser-foot acting on the body of the material in substantial cross-line with the rear edge of the folding face of said folder, a fold-layer, and a fold-buckling device acting on the base of the fold of the margin between said folder and said fold-layer adjacent to said rear edge of said folding face.
9. In a folding machine for folding the margin of flexible material, the combination of step-by-step feeding means, a folder for partially forming the fold of the margin, a pressure-foot acting on the body of the material in substantial cross-line with the rear edge of the folding face of said folder, a fold-layer, a fold-buckling device acting on the base of the fold of the margin between said folder and said fold-layer adjacent to said rear edge of said folding face, and a buckling device acting on the body of said margin adjacent to said cross-line.
10. In a folding machine for folding the margin of flexible material, the combination of step-by-step feeding means, a folder, a fold-buckling device, a fold-presser, and a fold-layer movable forward and back between said fold-buckling device and fold-presser. 100
105
11. In a folding machine for folding the margin of flexible material, the combination of step-by-step feeding means, a folder, a fold-buckling device, a fold-presser, and a fold-layer movable forward and back between said fold-buckling device and fold-presser, and means under the control of the operator during the feeding and folding operations of the machine for effecting said movements of said fold-layer. 110
115
12. In a folding machine for folding the margin of flexible material, the combination of step-by-step feeding means, a folder, a fold-buckling device, a fold-presser, a fold-layer movable forward and back between said fold-buckling device and fold-presser, means under the control of the operator during the feeding and folding operations of the machine for effecting said last-named movements, and resilient means for normally moving said fold-layer to one limit of its path. 120
125
13. In a folding machine for folding the margin of flexible material, the combination 130

- of step-by-step feeding means, a folder, a fold-buckling device, a fold-presser, a fold-layer movable forward and back between said fold-buckling device and fold-presser, means under the control of the operator during the feeding and folding operations of the machine for effecting said movements of said fold-layer, and means for adjusting one of the limits of movement of said fold-layer.
14. In a folding machine for folding the margin of flexible material, the combination of step-by-step feeding means, a folder, a presser-foot opposite said folder, a fold-layer shiftable forward and back, and a fold-buckling device between said folder and fold-layer, said fold-layer when in forward position extending in a direction crosswise of the fold being laid and toward the cross plane in which said folder is located.
15. In a folding machine for folding the margin of flexible material, the combination of step-by-step feeding means, a folder, a presser-foot opposite said folder, a fold-layer shiftable forward and back, and a fold-buckling device between said folder and fold-layer having a fold-buckling edge, said fold-layer when in forward position intersecting the cross plane in which said fold-buckling edge is located and extending in a direction crosswise of the fold being laid.
16. In a folding machine for folding the convexly curved margin of flexible material, the combination of step-by-step feeding means, a fold-layer having a narrow fold-pressing face extending crosswise of the fold of the margin being pressed and having relief at each side thereof from pressure upon said fold for pressing said fold in narrow successive cross-lines which are spaced apart and converge toward the normally free edge of the fold being laid for forming pockers, and a buckling device acting in advance of said fold-layer on the base of the fold being made by said folder.
17. In a folding machine for folding the convexly curved margin of flexible material, the combination of step-by-step feeding means, a fold-layer having a narrow fold-pressing face extending crosswise of the fold of the margin being pressed and having relief at each side thereof from pressure upon said fold for pressing said fold in narrow successive cross lines which are spaced apart and converge toward the normally free edge of the fold being laid for forming pockers by successive fold-laying and pressing actions of said fold-layer, and a buckling device acting in advance of said fold-layer on the bases of the pockers being formed between said successive actions.
18. In a folding machine for folding the margin of flexible material having a convexly curved edge, the combination of step-by-step feeding means, a folder acting to partially turn the fold of the margin, a presser-foot acting opposite to said folder, said material arranged to be turned in feeding the same upon a curve having the center from which its convex edge is described substantially as a center, and a shiftable fold-layer shiftable forward and back and extending when in forward position crosswise of the fold being laid slantingly from a point to rear of said folder toward said center.
19. In a folding machine for folding the margin of flexible material having a convexly curved edge, the combination of step-by-step feeding means, a folder acting to partially turn the fold of the margin, a presser-foot acting opposite to said folder, said material arranged to be turned in feeding the same upon a curve having the center from which its convex edge is described substantially as a center, a shiftable fold-layer shiftable forward and back and extending when in forward position crosswise of the fold being laid from a point to rear of said folder toward said center, and a fold-buckling device acting on the base of the fold of said margin between said folder and fold-layer.
20. In a folding machine for folding the margin of flexible material, the combination of step-by-step feeding means, a folder, a fold-buckling device, an adjustable fold-layer adjustable forward and back crosswise of the margin being folded, and a fold-presser, said folder, fold-buckling device, fold-layer and fold-presser acting progressively on the margin of the material in the order named.
21. In a folding machine for folding the margin of flexible material, the combination of step-by-step feeding means, a folder, a pivoted fold-layer acting on the margin of the material subsequent to said folder, a lever on which said fold-layer is pivoted, and means for shifting said fold-layer comprising an arm having a portion curved substantially on an arc described from a center coincident with the pivotal axis of said lever.
22. In a folding machine for folding the margin of flexible material, the combination of step-by-step feeding means, a folder, a pivoted fold-layer acting on the margin of the material subsequent to said folder, a lever on which said fold-layer is pivoted, means for shifting said fold-layer comprising an arm having a portion curved substantially on an arc described from a center coincident with the pivotal axis of said lever, and means for adjustably limiting said shifting.
23. In a folding machine for folding the margin of flexible material, the combination of step-by-step feeding means, a folder, a pivoted fold-layer acting on the margin of

- the material subsequent to said folder, a lever on which said fold-layer is pivoted, means for shifting said fold-layer comprising an arm having a portion curved substantially on an arc described from a center coincident with the pivotal axis of said lever, and means under the control of the operator during the feeding movements of the material for shifting said arm.
24. In a folding machine for folding the margin of flexible material, the combination of step-by-step feeding means, a folder, a pivoted fold-layer acting on the margin of the material subsequent to said folder, a lever on which said fold-layer is pivoted, means for shifting said fold-layer comprising an arm having a portion curved substantially on an arc described from a center coincident with the pivotal axis of said lever, and means under the control of the operator during the feeding movements of the material for adjustably limiting said shifting.
25. In a folding machine for folding the margin of flexible material, the combination of step-by-step feeding means, a folder, a presser-foot acting opposite thereto, a pivoted fold-layer acting on the margin subsequent to said folder, a rock-shaft having operative connection with said feeding means, and a lever pivoted about the axis of said rock-shaft and under the manual control of the operator during said feeding movements, said lever having operative connection with said fold-layer for adjusting its crosswise position on the margin being laid.
26. In a folding machine for folding the margin of flexible material, the combination of step-by-step feeding means, a folder, a presser-foot acting opposite thereto, a pivoted fold-layer acting on the margin subsequent to said folder, a rock-shaft having operative connection with said feeding means, a lever pivoted about the axis of said rock-shaft and under the manual control of the operator during said feeding movements, said lever having operative connection with said fold-layer for adjusting its crosswise position on the margin being laid, and resilient means for normally returning said last-named lever to one limit of its path.
27. In a folding machine for folding the margin of flexible material, the combination of a folder, a presser-foot, the rear ends of said folder and presser-foot being in substantial cross-line with each other, a material-supporting table having a material-supporting surface, said material-supporting surface having a depression therein at the side of said folder, the rear wall of said depression being substantially at said cross-line, a fold-presser acting in rear of said folder and depression, and step-by-step feeding means acting at the side of said folder comprising a member forming the bottom for said depression and an upper feeding part above said bottom for feeding the material and forming a depressed portion therein at the side of said folder and in front of said fold-layer.
28. In a folding machine for folding the margin of flexible material, the combination of a folder, a material-supporting table having a material-supporting surface, said material-supporting surface having a depression therein at the side of said folder, a fold-presser acting in rear of said folder, and step-by-step feeding means acting at the side of said folder, said feeding means comprising a reciprocating bar forming the bottom of said depression and a feeding part above said bar having reciprocating and up and down movements for feeding the material between said feeding part and bar.
29. In a folding machine for folding the margin of flexible material, the combination of a folder, a material-supporting table having a material-supporting surface having a depression therein at the side of said folder, a fold-presser acting in rear of said folder, step-by-step feeding means acting at the side of said folder, said feeding means comprising a reciprocating bar forming the bottom of said depression, a feeding part above said bar having reciprocating and up and down movements for feeding the material between said feeding part and bar, and anti-friction rollers upon which said bar is mounted.
30. In a folding machine for folding the margin of flexible material, the combination of a folder, a material-supporting table having a material-supporting surface having a depression therein at the side of said folder, a fold-presser acting in rear of said folder, step-by-step feeding means acting at the side of said folder, said feeding means comprising a reciprocating bar forming the bottom of said depression, a feeding-part above said bar having reciprocating and up and down movements for feeding the material between said feeding part and bar, and resilient means for normally returning said bar to one limit of its movements.
31. In a folding machine for folding the margin of flexible material, the combination of step-by-step feeding means, a folder for partially folding the margin, and a fold-hammer comprising a forward fold-pressing part, a rear fold-pressing part, and a fold-layer adjustable between said fold-pressing parts for extending in different directions crosswise of the fold of the margin in a plane substantially parallel to the plane of said margin when in fold-pressing relation.
32. In a folding machine for folding the margin of flexible material, the combination of step-by-step feeding means, a folder

for partially folding the margin, and a fold-hammer comprising a forward fold-pressing part, a rear fold-pressing part, a fold-layer adjustable between said fold-pressing parts for extending in different directions crosswise of the fold of the margin in a plane substantially parallel to the plane of said margin when in fold-pressing relation, and means under the control of the operator during the operation of the machine for adjusting said fold-layer.

33. In a folding machine for folding the margin of flexible material, the combination of step-by-step feeding means, a folder for partially folding the margin, and a fold-hammer comprising a forward fold-pressing part, a rear fold-pressing part, and a fold-layer adjustable between said fold-pressing parts for extending in different directions crosswise of the fold of the margin in a plane substantially parallel to the plane of said margin when in fold-pressing relation, means under the control of the operator during the operation of the machine for shifting said fold-layer, and means for

adjustably limiting the length of path of shifting movement of said fold-layer.

34. In a folding machine for folding the margin of flexible material, the combination of step-by-step feeding means, a folder for partially folding the margin, and a fold-hammer comprising a forward fold-pressing part, and a rear fold-pressing part, and a fold-layer adjustable between said fold-pressing parts for extending in different directions crosswise of the fold of the margin in a plane substantially parallel to the plane of said margin when in fold-pressing relation, means under the control of the operator during the operation of the machine for shifting said fold-layer, and means for normally returning said fold-layer to one limit of its path.

In testimony whereof, I have hereunto signed my name in the presence of two ⁴⁵ subscribing witnesses.

WILLIAM F. LAUTENSCHLAGER.
